ABSTRACT

Highly alkaline detergents for foam cleaning contain, as the foaming additive, sodium salts of fatty acid sulfonates, amine oxides, amido alkyl amine oxides, substitution derivative of imidazoline alkanoic quaternary ammonium hydroxide, and mixtures thereof.

8 Claims, No Drawings

FOAMED DETERGENT COMPOSITION

This invention relates to foam cleaning compositions which are highly alkaline.

In summary, the foam cleaning compositions of this invention contain, as essential ingredients, from 10 to 90 weight percent sodium hydroxide, from 5 to 25 weight percent sodium tripolyphosphate, from 0 to 50 weight percent trisodium phosphate, from 10 to 30 weight percent soda ash, from 0 to 5 weight percent calcium silicate, and from 4 to 10 weight percent of a foaming additive. Suitable foaming additives include sodium salts of fatty acid sulfonates, amine oxides having the formula:

wherein R and R₁ are alkyl groups having from one to 34 carbons or hydroxy alkyl groups having from two to 34 carbons, and R₂ is an alkyl group having from six to 32 carbons; amido alkyl amine oxides having the formula:

wherein

is an acyl radical selected from the group of acyl radicals having from 10 to 16 carbons, and R₄ and R₅ are alkyl radicals having from one to four carbons; amphoteric compounds having the formula:

wherein R₆ is a hydrocarbon radical having from four to 18 carbons, R₇ is a hydrocarbon radical having from one to four carbons, R₈CO is a acyl radical having from one to four carbons, X is H, Na, K, —CH₂COONa, —CH₂COOK or —CH₂COOH, and Y is H, Na or K; and mixtures of two or more of the above foaming additives. This invention also includes foam cleaning solutions containing from 1.5 to 12 weight percent of the above compositions, formed from a premix of the ingredients or by mixing the individual ingredients with water.

Foam cleaning is effected by pumping high foam cleaning solutions in a mechanical system in which compressed air is mixed with the cleaning solution to produce a stable, copious foam, and applying the foam to a soiled surface. The "dry" foam clings to the surface to be cleaned, increases the contact time of the liquid with the soil and prevents rapid drying or run-off of the liquid cleaner, thereby dramatically improving the cleaning. Foam cleaning has several advantages. It reduces the amount of solution required for cleaning. It prevents the splashing experienced in spray cleaning. With foam it is possible to apply cleaning solutions into duct work and pipings, and to the underside and poorly accessible parts of machinery and equipment where spray cleaning is impractical. It prevents the irritating vapors of liquid solutions from distilling into the air. It also reduces the cost of labor, time and materials. Foam cleaning has been shown to be effective for cleaning trucks, tractor trailers, aircraft, factory walls, and ceilings. It is effective for alkaline paint stripping and for other applications of solvent-type paint stripping from large surfaces such as storage tanks, walls and ceilings, aircraft and tractor trailers.

One example of a prior industrial foam cleaning procedure is described in U.S. Pat. No. 3,037,887, the entire disclosure of which is incorporated herein by reference for background information.

5 Although a wide variety of surface active agents are commercially available, many of them identified as foaming agents, most of them will not provide a high foaming action in highly alkaline solutions which are required for cleaning applications.

10 It is the object of this invention to provide a foam cleaning composition which has a high foam characteristic even though it is very alkaline. It is another object of this invention to provide aqueous solutions of this highly foamable alkaline cleaning composition.

15 The foaming additives which can be used in the composition of this invention include sodium salts of fatty acid (10-22 carbons) sulfonates such as fatty acid sulfonates derived from oleic acid, linoleic acid, linolinic acid, eleosteric acid, licanic acid, palmitoleic acid, petroselenic acid, erusic acid and the like. The preferred fatty acid sulfonate is the sodium salt of sulfonated oleic acid.

20 Amine oxides can also be used as the foaming additive in the composition of this invention. Suitable amine oxides include those having the formula:

25 wherein R and R₁ are alkyl groups having from one to 34 carbons or hydroxy alkyl groups having from two to 34 carbons, and R₂ is an alkyl group having from six to 32 carbons. Amine oxides of this type are disclosed in U.S. Pat. No. 3,270,060 and include acetyl dimethyl amine oxide, myristyl-cetyl dimethyl amine oxide, myristyl dimethyl amine oxide, stearyl dimethyl amine oxide, bis (2 hydroxyethyl) alkyl amine oxide, and the like.

30 35 Other useful foaming additives include amido alkyl amine oxides having the formula:

wherein

45 50 is an acyl radical selected from the group of acyl radicals having from 10 to 16 carbons, and R₄ and R₅ are alkyl radicals having from one to four carbons. Foaming agents of this type are disclosed in Canadian Pat. No. 724,663 and include compounds wherein the acyl group is derived from capric, undecanoic, tridecanoic, myristic, pentadecanoic, and palmitic acids, for example.

55 60 Highly effective foaming additives which can be used in the composition of this invention include amphoteric compounds having the formula:

65 70 wherein R₆ is a hydrocarbon radical having from four to 18 carbons, R₇ is a hydrocarbon radical having from one to four carbons, R₈CO is an acyl radical having from one to four carbons, X is Na, K, H, —CH₂COONa, —CH₂COOK or —CH₂COOH, and Y is H, Na or K.

CH_2COOH ; and Y is H, Na, or K. Amphoteric foaming additives of this type are disclosed in U.S. Pat. Nos. 2,528,378 and 2,773,068. The preferred amphoteric foaming agents are those according to the formula wherein R_6 has 8 carbons and R_7 and $R_8\text{CO}$ each have two carbons; and those compounds according to the formula where R_6 has 11 carbons, R_7 and $R_8\text{CO}$ each have two carbons, and X and Y are Na, K, or H.

The foaming additives are mixed with alkali metal (preferably sodium) hydroxides, pyrophosphates, tripolyphosphates, orthophosphates, carbonates, silicates, and metasilicates to form compositions of these components having the concentration ranges shown in Table A.

TABLE A

Ingredient	Preferred	Wt. % Optimum
Alkali metal hydroxide	10-90	20-70
Tetra alkali metal pyrophosphate	5-25	5-10
Alkali metal tripolyphosphate	5-25	5-10
Alkyl metal phosphate	0-50	0-20
Alkali metal carbonate	0-30	0-10
Alkali earth metal silicate	0-5	0-3
Sodium metasilicate	0-50	4-10
Foaming additive	4-10	4-10

Aqueous solutions containing from 1.5 to 12 and preferably from 3 to 8 weight percent of these compositions are highly effective foam cleaning compositions. The aqueous solutions can be made by mixing water with a previous mix of the foaming additive together with the other ingredients, or it can be formed by sequential addition of the individual ingredients or combinations of ingredients to water.

For cleaning with aqueous solutions of this invention, the solution is mixed with sufficient air to form a "dry" foam in a foaming device such as described in copending application Ser. No. 534,378 filed Mar. 15, 1966, and is applied to the surface to be cleaned.

This invention is further illustrated by the following specific but non-limiting examples.

Dry powder compositions containing 60 percent sodium hydroxide, 5 percent tetrasodium pyrophosphate, 5 percent sodium tripolyphosphate, 2 percent calcium silicate, 13 percent sodium metasilicate, and 4, 6, and 10 percent concentrations of each of the foaming additives shown in Table B were formulated. These compositions are dry, stable powder compositions. Solutions of these compositions in concentrations of from 1.5 to 12 percent produce a dry and copious foam when mixed with air.

Aqueous solutions of these dry powder mixtures are mixed with water in amounts sufficient to provide the foaming additive concentrations shown in Table B. Column A lists dilute concentrations, Column B lists immediate (preferred) concentrations and Column C lists higher concentrations.

TABLE B

Ex.	Foaming Additive	Concentration, Wt. %		
		A	B	C
1	Sodium salt of sulfonated oleic acid (Sul-Fon-Ate OA5)	0.3%	0.7%	1.5%
2	Dicarboxylic caprylic and ethylhexanoic acid cycloimidate salt (Miranol-JEM)	0.3%	0.8%	1.5%
3	Dicarboxylic coconut fatty acid cycloimidate (Miranol-C2M-SF)	0.3%	0.8%	1.5%
4	Dicarboxylic coconut fatty acid cycloimidate	0.3%	0.8%	1.5%

5	salt cycloimidate (Miranol-C2M)	0.3%	0.6%	1.3%
6	Acetyl dimethylamine oxide (Ammonyx Co)	0.3%	0.6%	1.3%
7	Myristyl-cetyl dimethyl amide oxide (Ammonyx MCO)	0.3%	0.6%	1.3%
8	Myristyl dimethyl amine oxide (Ammonyx MO)	0.3%	0.6%	1.3%
9	Stearyl dimethyl amine oxide (Ammonyx SO)	0.3%	0.6%	1.3%
10	Bis (2-hydroxyethyl) alkyl amine oxide (Aromox C)	0.5%	1.0%	2.0%
11	Dimethyl alkylamine oxide (Aromox CD)	0.4%	0.8%	1.6%
12	Alkyl dimethyl amine oxide (Textamine CA)	0.65%	0.8%	2.60%
13	Amido alkyl amine oxide (Textamine 1839)	0.5%	1.0%	2.0%
14	Tertiary amine oxide (Leyco Amine Oxide C-50)	0.4%	0.8%	2.0%

The foamable solutions of Table B form dry and copious foams when mixed with air with a suitable foaming apparatus such as a FOAM-ALL foam generator sold by DuBois Chemicals Division of W. R. Grace & Co.

Obviously, many modifications and variations of the invention as hereinabove set forth can be made without departing from the essence and scope thereof, and only such limitations should be applied as are indicated in the claims.

The invention claimed is:

1. A powder foam cleaning composition consisting essentially of:
  - a. from 10 to 90 wt. percent sodium hydroxide,
  - b. from 5 to 25 wt. percent tetrasodium pyrophosphate,
  - c. from 5 to 25 wt. percent sodium tripolyphosphate,
  - d. from 0 to 50 wt. percent trisodium phosphate,
  - e. from 0 to 30 wt. percent soda ash,
  - f. from 0 to 5 wt. percent calcium silicate,
  - g. from 0 to 5 wt. percent sodium metasilicate, and
  - h. from 4 to 10 wt. percent of a foaming additive selected from the group consisting of:
    1. sodium salts of fatty acid sulfonates,
    2. amine oxides having the formula

50 wherein R and R_1 are alkyl groups having from one to 34 carbons or hydroxy alkyl groups having from two to 34 carbons, and R_2 is an alkyl group having from six to 32 carbons,

3. amido alkyl amine oxides having the formula

55 60 wherein

65 is an acyl radical selected from the group of acyl radicals having from 10 to 16 carbons, and R_4 and R_5 are alkyl radicals having from one to four carbons, and

4. amphoteric compounds having the formula:

wherein R_6 is a hydrocarbon radical having from four to 18 carbons; R_7 is a hydrocarbon radical having from one to four carbons; R_8CO is an acyl radical having from one to four carbons; X is Na, K, H, $-\text{CH}_2\text{COONa}$, $-\text{CH}_2\text{COOK}$, or $-\text{CH}_2\text{COOH}$ and Y is Na, K or H.

2. An aqueous foam cleaning solution of from 1.5 to 12 wt. percent of the powder composition of claim 1.
3. The powder cleaning composition of claim 1 wherein the foaming additive is sodium oleate sulfonate.
4. The powder cleaning composition of claim 1 wherein the foaming additive is the amphoteric compound wherein R_6 has

eight carbons, and R_7 and R_8CO each have two carbons.

5. The powder cleaning composition of claim 1 wherein the foaming additive is the amphoteric compound wherein R_6 has 11 carbons and R_7 and R_8CO each have two carbons.

- 5 6. The powder cleaning composition of claim 1 wherein the foaming additive is the amine oxide (h) (2) wherein R and R_1 are methyl groups.

7. The powder cleaning composition of claim 1 wherein the foaming additive is the amine oxide (h) (2) wherein R and R_1 10 are hydroxyethyl groups.

8. The powder cleaning composition of claim 1 wherein the foaming additive is the amido alkyl amine oxide.
